UNITED STATES PATENT OFFICE

HEINRICH KÜCHENMEISTER, OF BERLIN, GERMANY

ACOUSTIC APPARATUS, PARTICULARLY SIGNALING APPARATUS

Application filed October 4, 1926, Serial No. 139,547, and in Germany October 28, 1925.

It is already known that the volume of a sound can be amplified and its carrying capacity multiplied by artificially setting up a phase displacement and by suitably selecting the resulting interval in a definite succession of sounds.

The present invention makes use of this known fact in order to set up, for example in the case of acoustic signals that are to be clearly audible at a distance, those conditions which, by generating the sound repeatedly at predetermined intervals, impart the so-called carrying volume to the resulting sound.

Acoustic signals of this kind are required, for example, in the case of sirens, double-bell signals, fire-alarm signals, factory time signals, foghorns, danger signals on the high seas, &c. For use at sea, in particular, the problem is not to disturb or even alarm the unconcerned coastal population or the passengers aboard ship by a signal in the form of a shrill, loud note, discord or dissonance, but to produce a signal which, without being disturbing, has a wide effective range corresponding to the special circumstances, and the intensity of which can be controlled from a receiving station far removed from the sending station. Contrary to previous thought, the problem cannot be solved by generating a very powerful note for emission, by means of externally supplied extraneous energy; but it can be solved by imparting to the note or notes, at the time of production at the sending station, those specific properties which enable them to act on the organs of hearing at remote receiving stations, by reason of their ample volume, both by means of longitudinal waves and also, in suitable places, by means of transverse waves.

According to the invention, this result is achieved by repeatedly exciting the signaling instrument or apparatus in question by separate impulses that succeed each other at intervals of less than one third of a second.

By way of example, several acoustic sig-

naling generators suitable for carrying the invention into practice are illustrated in the accompanying drawing.

Figs. 1 and 2 show, in section and front elevation respectively, a siren operated by compressed air; Fig. 3 is a steam whistle, with double pipe; and Figs. 4, 5 and 6 show a double-bell signaling device in side elevation, part front elevation and perspective view respectively.

With reference to Fig. 1, it should be stated that the intention is to operate in known manner, through the compressed air pipe *a*, a siren consisting of a perforated rotating disc *b* and a fixed perforated disc *c*, both of which are enclosed in a casing *d*. The holes in the rotary disc *b* are marked *f*, and those in the fixed disc *c* are marked *e*. The number of holes *e*: *f*, the number of revolutions of the disc *b*, and the air pressure are selected so that—taking the rotational velocity into consideration—identical sound impulses are generated at intervals of about $\frac{1}{4}$ th to (for example) $\frac{1}{80}$ th of a second. In this way a full note is produced, the range of which will be the greater in proportion as the selected interval increases. The explanation of the effect is that, under certain conditions—ascertained by experiment and afterwards selectively adjustable—an assimilation and accretion of the sound waves takes place at remote distances, thus increasing the audibility, and producing a sound that has a soothing effect on the human ear.

The limit in the selection of the interval is the distance at which the sounds no longer superimpose even further away. According to the invention, a plurality of successively produced sounds—equal energy of excitation being premised—carry very much further than a sound generated continuously by the usual sirens which, as is known, run at very high speeds; and this is quite apart from the consideration that the character of such a

sound is unnecessarily disturbing, disagreeable and shrill.

A signal generator in the form of steam whistles (Fig. 3) can be employed in the same way. The steam whistles themselves are denoted by k' and k^2 ; the casing by i ; and the control valve, or similar regulating device, by g . In the manner already described, the steam whistles are excited in repeated succession and at predetermined intervals under the control of the valve g which has ports h and revolves at a determined speed. The steam may be replaced by compressed air, thus giving a pneumatic whistle.

The desired effect can be obtained by mounting the two steam whistles k' and k^2 side by side as shown and making the impulse for the second note commence before the note first produced has completely subsided. This can be done by arranging the spacing of the ports h and suitably adjusting the number of revolutions of the valve g . In Fig. 3, the whistles are both of approximately equal size, because they are intended to produce only a slight difference in tone for sound oscillations. If the signal is to be of the double-note type, the whistles k' and k^2 must differ substantially from each other in respect of length and other particulars.

Figs. 4, 5 and 6 represent the application of the invention to a double-bell signaling device in which the bells are tuned to different notes, for example A and G-sharp. $l:l$ denote two shafts each provided with adjustable cams $m:m$ having a definite offset, said cams acting in known manner on the hammers n of bells o . The shafts $l:l$ are connected together, and uniform speed is obtained, by means of a connection p , which may be of the belt, chain, rope or cord type. To allow for slip, the pulley of the driven shaft may be of slightly larger diameter than the pulley of the driving shaft.

The effect of this double-bell signaling device is intensified by repeatedly exciting two (or more) bells having the same fundamental note at an optimum interval which must first be ascertained by experiment. In parallel therewith, or also offset by the selected interval, a sound of different pitch is superimposed in the same manner, thus producing an agreeable resultant note of wide range.

The invention resides, not in the production of a sound which shall be particularly loud in the immediate vicinity of the signaling device, but rather in obtaining the most favourable transmission of sound to selected distances from the signaling device, thereby to obtain an optimum effect. In this connection it is an important point that the dimensions of the intervals can be modified in accordance with the distance effect, by correspondingly controlling the excitation of the sound, while the device is working.

Having now fully described my invention,

what I claim and desire to secure by Letters Patent is:—

1. A method of audible signaling consisting in repeatedly exciting a sound generator by individual sound impulses that succeed one another at intervals of less than one third of a second.

2. Acoustic apparatus comprising a sound generator and means whereby the sounds to be emitted from said generator can be excited by individual impulses that succeed one another at intervals of less than one third of a second.

3. Acoustic apparatus comprising a sound generator, means whereby sounds can be excited from said generator, and means for controlling said excitation to ensure individual sound impulses that succeed one another at intervals of less than one third of a second.

4. Acoustic apparatus comprising a plurality of sound emitters, means for repeatedly exciting said emitters with a phase displacement to ensure that an impulse for one emitter begins before an impulse for another emitter has ceased, and means whereby the individual sound impulses from each emitter can be made to succeed one another at intervals of less than one third of a second.

5. Acoustic apparatus comprising a plurality of sound emitters of different pitch, means for repeatedly exciting said emitters with a phase displacement to ensure that an impulse for one emitter begins before an impulse for another emitter has ceased, and means whereby the individual sound impulses from each emitter can be made to succeed one another at intervals of less than one third of a second.

6. Acoustic signaling apparatus comprising a hollow casing for the admission of pressure fluid, means associated with the casing upon which said fluid acts to generate sound waves, and means for repeatedly interrupting the action of said fluid to give sound impulses that succeed one another at less than one third of a second.

7. Acoustic signaling apparatus comprising a hollow casing for the admission of pressure fluid, means associated with the casing upon which said fluid acts to generate sound waves, and a perforated member movable in the casing for repeatedly interrupting the action of said fluid to give sound impulses that succeed one another at less than one third of a second.

8. Acoustic signaling apparatus comprising a hollow casing having inlet and outlet openings for the passage therethrough of pressure fluid, and a member rotatable in the casing past said outlet openings to produce by said pressure fluid sound impulses that succeed one another at an interval of less than one third of a second.

9. Acoustic signaling apparatus comprising a hollow casing having an inlet for pres-

sure fluid, whistle pipes in communication with the casing, and a member rotatable in the casing past the inlets to said pipes in order to produce by said pressure fluid sound impulses that succeed one another at an interval of less than one third of a second.

10. Acoustic apparatus comprising a sound generator, means for successively exciting the sounds to be emitted from said generator by individual impulses that succeed one another at intervals of less than one third of a second, and means whereby said time interval can be adjusted.

11. Acoustic apparatus comprising a sound generator, means whereby sounds can be excited from said generator, and means for variably controlling said excitation to ensure individual sound impulses that succeed one another at intervals of less than one third of 20 a second.

12. Acoustic apparatus comprising a plurality of sound generators, means for repeatedly exciting said generators with a phase displacement to ensure that an impulse for one generator begins before an impulse for another generator has ceased, means whereby the individual sound impulses emitted from each generator can be made to succeed one another at intervals of less than one third 25 of a second, and means whereby said time interval can be adjusted.

13. Acoustic apparatus comprising a plurality of sound generators of different pitch, means for repeatedly exciting said generators 35 with a phase displacement to ensure that an impulse for one generator begins before an impulse for another generator has ceased, means whereby the individual sound impulses emitted from each generator can be 40 made to succeed one another at intervals of less than one third of a second, and means whereby said time intervals can be adjusted.

14. Acoustic signaling apparatus comprising a hollow casing for the admission of 45 pressure fluid, means associated with the casing upon which said fluid acts to generate sound waves, means for repeatedly interrupting the action of said fluid to give sound impulses that succeed one another at less than 50 one third of a second, and means whereby the time interval can be adjusted.

15. Acoustic signaling apparatus, comprising a hollow casing for the admission of pressure fluid, means associated with the casing 55 upon which said fluid acts to generate sound waves, a perforated member movable in the casing for repeatedly interrupting the action of said fluid to give sound impulses that succeed one another at less than one third of a 60 second, and means whereby the time interval can be adjusted.

16. Acoustic apparatus comprising a plurality of sound generators, and means for exciting sounds of different pitch from said 65 generators, each of said sounds being excited

by individual impulses that succeed one another at intervals of less than one third of a second.

17. Acoustic apparatus comprising a plurality of sound generators, and means for exciting in variable relation sounds of different pitch from said generators, each of said sounds being excited by individual impulses that succeed one another at intervals of less than one third of a second.

In testimony whereof I affix my signature.
